ACTING ATTORNEY

UNITED STATES PATENT OFFICE.

ALESSANDRO FORNER, OF NEW YORK, N. Y.

WINDOW-SCREEN.

1,233,658.

Specification of Letters Patent. Patented July 17, 1917.

Application filed January 29, 1915. Serial No. 5,092.

To all whom it may concern:

Be it known that I, ALESSANDRO FORNER, a citizen of the United States, and a resident of the city of New York, borough of 5 Manhattan, in the county and State of New York, have invented a new and Improved Window-Screen, of which the following is a full, clear, and exact description.

This invention relates to improvements in 10 window screens, and has for an object to provide an improved mechanical arrangement which does not permit any insect to enter a room.

Another object is to provide a special adjustment of springs to facilitate its operation.

Still another object is to provide proper means to install same wherever desired, as for example; between the window frame, as 20 shown in Fig. 3 or outside of the frame.

Referring to the drawings Fig. 1 is a sectional view of the adjustment showing its respective springs, pole and roller. Fig. 2 is an elevation view of the screen partially 25 rolled on the roller. Fig. 3 is a side sectional elevation of a window frame showing roller and screen. Fig. 4 is a front elevation of part of the guide one of which is mounted on each side of the window frame. Fig. 5 is a detailed view of the guide and 30 its adjustment slots. Fig. 6 is a side elevation of the duplex spring attached to the screen. Fig. 7 is a front view of Fig. 6. Fig. 8 is a cross sectional view of Fig. 4. Fig. 9 is a cross sectional view of Fig. 5.

Referring to the accompanying drawings by numerals.

Screen 1 is tightly attached to roller 2; pole 3 is set on supporters 4 in order that 40 when screen 1 is being pulled it will cause roller 2 to rotate; while roller 2 is rotating springs 5 and 6 will wind around pole 3 which is held by supporters 4. The metallic cords 7, attached to the side edges of the 45 screen 1, are adapted to traverse the grooved pulleys 8 and the slotted guide tubes 9 when a metal border plate 12, attached to the lower end of the screen and carrying the duplex springs 10, is grasped and pulled 50 downwardly in unrolling the screen. When the duplex springs 10 have reached the rods

14 which are stationary on the window frame and may be placed at any desired location, they will be engaged thus holding screen 1, preventing same from being rolled 55 back by springs 5 and 6.

When it is desired to roll the screen up, it is only necessary to apply a slight upward pressure or jerk to the plate 12, thereby disengaging the duplex springs 10 from the 60 keeper-rods 14, whereupon the springs 5 and 6 act on the roller 2 causing the screen to be wound thereon.

The slots 15 are for the purpose of adjusting the guides 9, so that they keep always 65 perpendicular and parallel the guides 9.

From the foregoing description it will be apparent that the invention provides an exceedingly inexpensive, simple and practicable mechanical arrangement; that it may 70 be installed on any of the present windows, and that it will be effective and reliable in operation.

While the preferred embodiment of the invention has been shown and described in 75 detail it will be understood that I do not wish to be limited to the construction set forth since various changes in the form, proportion and arrangement of parts and in the details of construction may be resorted to 80 without departing from the principle and scope of the invention.

Having thus described the invention, I claim:

1. A window screen mechanism having a 85 spring roller and a screen attached thereto, guideways for retaining the side edges of the screen when extended, stationary keeper rods, and means mounted on the screen for frictionally engaging said keeper rods for 90 holding the screen extended.

2. A window screen mechanism having a spring roller and a screen attached thereto, guideways for retaining the side edges of the screen when extended, stationary keeper 95 rods arranged in pairs with the members thereof disposed on opposite sides of the plane of the screen, and yielding means mounted on and carried by the screen for arrangement between the keeper rods to 100 frictionally engage same, for holding the screen extended.

3. A window screen mechanism having a spring roller and a screen attached thereto, guideways for retaining the side edges of the screen when extended, stationary keeper rods arranged in pairs in parallel relation, and curved spring holding means carried by the screen for interposition between said keeper rods to frictionally engage the same and hold the screen extended.
- 5

ALESSANDRO FORNER.
